UNITED STATES PATENT OFFICE.

CLARENCE H. BEASECKER, OF SPARTA, MICHIGAN.

MACHINE FOR REFACING VALVES.

Application filed March 7, 1921. Serial No. 450,389.

To all whom it may concern:

Be it known that I, CLARENCE H. BEASECKER, a citizen of the United States, residing at Sparta, in the county of Kent and

5 State of Michigan, have invented new and useful Improvements in Machines for Refacing Valves, of which the following is a specification.

The present invention relates to machines 10 for re-facing valves, such as are employed in internal-combustion engines and the like; and its object is, generally, to provide a machine of that character which may be economically manufactured and readily and 15 easily operated; and, more particularly to provide such a machine improved in various respects hereinafter appearing; and further, to provide improved means for moving the valve-rotating means of such a machine into 20 and out of operative engagement with the work; and further, to provide improved means for adapting such a machine to different kinds of such valves; and further, to provide improved means for adapting such a 25 machine to valves having stems of different diameters; and further, to provide an improved mounting for the operating crank of such a machine; and further, to provide improved means for ejecting a bushing in 30 which the valve stem rotates from such a machine; and further, to provide improved means for ejecting the valve from such a machine.

These and any other objects hereinafter 35 appearing are attained by, and the invention finds preferable embodiment in, the structure hereinafter particularly described and illustrated by the accompanying drawings, in which:—

40 Figure 1 is a top plan view of the lower portion of a machine for re-facing valves, sectioned on a horizontal plane corresponding to line 1—1 of Figure 2;

Figure 2 is a side view of the same, the 45 lower portion being diametrically sectioned on a vertical plane;

Figure 3 is a transverse sectional view of certain parts taken on planes corresponding to line 3—3 of Figure 2;

50 Figure 4 is a top plan view of a mounting for said machine, parts of the machine being shown sectioned on a horizontal plane corresponding to line 4—4 of Figure 2;

Figure 5 is a sectional view of said mount- 55 ing taken on a vertical plane corresponding

to line 5—5 of Figure 4, a portion of the machine being shown in side elevation; and

Figure 6 is a fragmentary side view of parts of said machine.

In the embodiment of the invention chosen for illustration by the drawings and for detailed description in the body of this specification, my valve re-facing machine has a body 1 having an opening 2 adapted to receive the stem 3 of the valve 4 whose circular bevelled edge portion 5 (which contacts the valve seat) is to be re-faced. Cutting means are carried in connection with the body 1, such means in the construction illustrated being the oppositely disposed cutters or bits 6 seated in vertical slots 7 in the block 8 and secured in such slots by set screws 9. This block is desirably removably secured to the body 1 in any suitable manner, as by the downwardly-extending lugs 10 of said block, seated in sockets 11 in the body 1. An arm 12 is swingably mounted on the body 1 at 13 on one side of the opening 2 and may be swung to the operative position of the machine shown in the drawings and secured in such position by suitable means as the pin 14 adapted to be thrust through orifices 15 in the lugs 16 of the body 1 at the side thereof opposite to the mounting 13, said pin also passing through an 85 orifice 17 in the free end of the arm 12. Means are rotatably mounted on the arm 12 for engaging the valve and rotating it in operative contact with the cutters 6, such

means comprising a shaft 18 rotatable in a bearing 19 on the arm and having a diametrically-extending end rib 20 adapted to engage in the kerf 21 of a valve 4 (as particularly shown in Figure 6); said shaft also has a collar 22 with spaced lugs 23 adapted to engage in the spaced sockets 24 of such a valve 4 as is shown in Figure 2. This collar 22 is movable longitudinally of the shaft to and from a position shown in Figure 2 in which position it is operative, 100 and is secured in such position as by a cotter pin 25. The cotter pin being removed, the collar may be detached, whereupon the rib 20 may be employed to engage the kerf 21 of such valves as are shown in Figure 6. 105

A crank 26 for rotating the shaft 18 may be swingably mounted at 27 on one side of the shaft's axis and thus rendered turnable to the position shown in Figure 2 wherein it engages between lugs 28, 29 carried by 110

the shaft at the opposite side of its axis from the mounting 27. By this arrangement the crank may be turned over to the left hand side of the machine shown in 5 Figure 2 when not in use, in which position the machine is more compact and occupies less space.

The opening 2 is of sufficient diameter to receive a bushing 30 fitting therein, and provided with a central bearing 31 in which the 10 valve stem 3 rotates. Bushings of the same outside diameter but whose bearings 31 are of different diameters being provided, valves having stems of different diameters corresponding to the bearings 31 of such bushings may be re-faced on the same machine. The opening 2 is internally threaded at 32 adjacent its lower end, a threaded member 33 turning on said threads. This member 33 15 has an axial bore 34 receiving a stop member 35 bored at 36 to receive the valve stem 3 and operating to limit the downward movement of said stem, this stop being adjustable by turning the member 33. The reduced lower portion 37 of this stop member 35 extends through the opening 38 in the lower end of the member 33 and may be 20 moved upwardly by hand or by a blow from a hammer, whereupon the valve's re-faced portion 5 will be ejected from the cutters; and the upward movement of the member 35 continuing, its upper edge 39 will then abut on and eject the bushing 30 from the opening 2. Before thus ejecting the bushing, the 25 chips resulting from the re-facing operation may be swept or blown out through the orifices 40 through the wall of the opening 2 so that they may not fall into the bottom portion of said opening.

30 The shank portion 41 of the body 1 is squared as shown and is non-turnably seated in a square socket 42 in the mounting member 43 which may be secured to the edge of a table or bench 44 by a screw 45.

35 The invention being intended to be pointed out in the claims, is not to be limited to or by details of construction of the particular embodiment thereof illustrated by the drawings or hereinbefore described.

40 **I claim:**

1. In a machine of the character described; a body having an opening adapted to receive the stem of a valve; cutting means carried in connection with the body; an arm 45 swingably mounted on the body at one side of said opening; means for securing the arm non-swingably to the body on the opposite side of said opening; means rotatably-mounted on the arm for engaging the valve 50 in the secured position of the arm and rotating the valve in operative contact with the cutting means and for releasing the valve in the non-secured position of the arm.

2. In a machine of the character described; a body having an opening adapted

to receive the stem of a valve; a block removably secured to the body and having cutting means; an arm swingably mounted on the body at one side of said opening; means for securing the arm non-swingably to the body on the opposite side of said opening; means rotatably-mounted on the arm for engaging the valve in the secured position of the arm and rotating the valve in operative contact with the cutting means and for releasing the valve in the non-secured position of the arm.

3. In a machine of the character described; a body having an opening adapted to receive the stem of a valve; cutting means carried in connection with the body; a rotatable shaft carried in connection with the body and having a diametrically-extending end rib adapted to engage in the kerf of a valve to rotate the valve in operative contact with the cutting means and having also a collar provided with spaced lugs adapted to engage in the spaced sockets of a valve to rotate the valve in operative contact with the cutting means, said collar being movable longitudinally of the shaft to and from a secured position thereon.

4. In a machine of the character described; a body having an opening adapted to receive the stem of a valve; cutting means carried in connection with the body; an arm swingably mounted on the body at one side of said opening; means for securing the arm non-swingably to the body on the opposite side of said opening; means rotatably-mounted on the arm for engaging the valve in the secured position of the arm and rotating the valve in operative contact with the cutting means and for releasing the valve in the non-secured position of the arm; a crank for rotating said rotatably-mounted means, swingably-mounted thereon at one side of the axis thereof and turnable into and out of engagement between lugs thereon at the opposite side of its said axis.

5. In a machine of the character described; a body having an opening adapted to receive the stem of a valve; cutting means carried in connection with the body; means for rotating the valve in operative contact with the cutting means; a bushing removably carried in said opening and having a bearing in which the valve stem rotates; a member in said opening and extending outside thereof and movable to positions in which it abuts on and ejects the bushing from said opening.

6. In a machine of the character described; a body having an opening adapted to receive the stem of a valve; cutting means carried in connection with the body; means for rotating the valve in operative contact with the cutting means; a member threaded in said opening; a member carried by the threaded member and extending outside

thereof and forming a stop for the end of the valve stem and movable relatively to the threaded member to positions in which it ejects the valve from the cutting means.

5 7. In a machine of the character described; a body having an opening adapted to receive the stem of a valve; cutting means carried in connection with the body; means for rotating the valve in operative contact 10 with the cutting means; a bushing removably carried in said opening and having a bearing in which the valve stem rotates; a member threaded in said opening; a member carried by the threaded member and extending outside thereof and forming a stop 15 for the end of the valve stem and movable relatively to the threaded member to positions in which it ejects the valve from the cutting means and to further positions in 20 which it abuts on and ejects the bushing from said opening.

8. In a machine of the character described; a body having an opening adapted to receive the stem of a valve; cutting means

carried in connection with the body; an arm 25 swingably mounted on the body; means rotatably mounted on the arm for engaging the valve in one swung position of the arm and rotating the valve in operative contact with the cutting means and for releasing the 30 valve in another swung position of the arm.

9. In a machine of the character described; a body having an opening adapted to receive the stem of a valve; a member carried by the body having a bearing for 35 the valve's stem; cutting means carried in connection with the body; an arm swingably mounted on the body; means rotatably mounted on the arm for engaging the valve in one swung position of the arm and rotating the valve in operative contact with the cutting means and for releasing the 40 valve in another swung position of the arm.

In testimony whereof I have hereunto set my hand at Grand Rapids, Michigan, this 45 3rd day of March, 1921.

CLARENCE H. BEASECKER.
